UNITED STATES PATENT OFFICE.

MORRIS LOWY, OF NEW YORK, N. Y.

CORNER FASTENING FOR BEDSTEADS.

Application filed October 26, 1921. Serial No. 510,416.

To all whom it may concern:

Be it known that I, MORRIS LOWY, a citizen of the United States, and resident of the city of New York, in the county of 5 Kings and State of New York, have invented certain new and useful Improvements in Corner Fastenings for Bedsteads, of which the following is a specification.

The present invention relates to improvements in corner-fastenings for bedsteads, and has for its main object to provide a simple, efficient and durable device of this 10 type which is made by stamping operations.

Another object of the invention is to produce a corner-fastening of the type specified, which permits of a convenient assembling of the bed and of a taking down of 15 the same by inexperienced operators with but little time and energy.

20 A further object of the invention is to so construct the corner-fastening that the bed-bottom supporting member may be clamped thereto or released therefrom by an element that forms part of the corner-fastening, there being thus no chance of 25 losing or misplacing the clamping member.

A still further object of the invention is to so construct the corner-fastening that the bed-bottom supporting angle bar may 30 be reversibly secured thereto, so as to adapt it to ordinary spring mattresses and also to box springs.

With these and other objects in view, which will more fully appear as the nature 35 of the invention is better understood, the same consists in the combination, arrangement and construction of parts hereinafter described, pointed out in the appended claims and illustrated in the accompanying drawings, it being understood that many 40 changes may be made in the size and proportion of the several parts and details of construction within the scope of the appended claims, without departing from the spirit or sacrificing any of the advantages 45 of the invention.

One of the many possible embodiments of the invention is illustrated in the accompanying drawings, in which:—

50 Figure 1 is a perspective view of a portion of the corner-post of a bedstead, with a corner-fastening, constructed in accordance with the present invention, in position thereon, the bed-bottom supporting angle bar being shown in position to receive an ordinary spring mattress; Fig. 2 is a side

55 elevation of the elements shown in Fig. 1; Fig. 3 is a section taken on line 3—3 of Fig. 2; Fig. 4 is a section taken on line 4—4 of Fig. 2; Fig. 5 is a plan view, partly in section, of the corner-fastening, showing the bed-bottom supporting angle bar positioned to receive a box spring; Fig. 6 is a perspective view of one of the 60 ends of the angle bar; Fig. 7 is a plan view of the blank of which the shell of the fastening is made.

In the drawings, the numeral 10 indicates a portion of a rectangular corner-post of a bedstead, to which the corner-fastening is to be attached. The corner-fastening includes a bracket-like hollow rectangular shell 11, preferably, made of one integral piece, for instance, by stamping operations from a blank 12, shown in Fig. 7 of the drawings. This shell includes a top wall 13, an inner side wall 14, an outer side wall 15, from which extends inwards, toward the wall 14, a bottom portion 16. From the said bottom portion rises a plate 80 member 17, the upper section of which is inclined, as shown at 18, said inclined portion extending toward the upper edge of the outer side wall 15. The elements of the shell so far described extend longitudinally of the bedstead, that is to say at right angles to the longitudinal axis of the corner post 10, and serve to receive, in a manner hereinafter to be described, the bed bottom supporting angle bar 19. The shell 90 includes furthermore end members 20, one of which engages the corner-post, while the other abuts against the first-mentioned end member. The end members project a substantial distance below the bottom portion 16 above referred to, screw bolts 21, passing through the said end members into the corner-post, serving to attach the shell to the said post. The inner end wall 14 extends down to the lower edge of one of the end members 20, to make the construction 95 as rigid as possible.

The shell, as described, constitutes a hollow rectangular body, adapted to receive one end of the angle bar 19. Adjacent its end, 105 the flange 22 of the angle bar is partly cut off, as shown at 23, there being an oblong piece removed, the length of which corresponds substantially to that of the top wall 13 of the shell 11, while its width is somewhat less than the height of the flange 22, thus leaving a strip 24 on the flange adja-

cent the bend 25 in the angle bar. The free edge of the other flange 26 of the angle bar is bent inwards, as shown at 27, throughout a length corresponding substantially to the length of the top 13 of the shell. This arrangement permits of inserting the angle bar into the shell in two positions. In one of the positions, shown in Figs. 1 to 4, inclusive, the flange 26 constitutes the horizontal flange of the angle bar, the other flange, denoted by the numeral 22, being disposed vertically and below the flange 26. When so inserted, the flange 26 abuts against the inner face of the top wall of the shell and the strip 24 against the inner face of the outer side wall 15 of the shell. In the other position, shown in Fig. 5 of the drawings, the flange 26 forms the vertical flange of the angle bar and the flange 22 the horizontal flange, the cut out portion 23 being provided to permit of an insertion of the angle bar in this manner. The inwardly bent portion 27 of the flange 26 projects in this position toward the inclined portion 18 of the plate member 17, for a purpose hereinafter to be described.

The plate member 17 and its inclined portion 18 are capable of yielding, constituting thus a jaw that is adapted to be forced 30 against the angle bar 19. For effecting this clamping operation, there is a lever 28 pivoted to the shell 11, the pivot being in the form of a screw bolt 29, that extends through the inner wall 14 of the shell and through 35 the plate member 17. The lever is provided with a side cam face 30, adapted to co-operate with a lug 31, formed upon the plate member 17. The lever is furthermore provided with an end cam face 32, capable of 40 co-operating with the flange 26 of the angle bar 19. The two cam faces mentioned are on a vertically extending section 33 of the lever, the latter being provided with a horizontally extending handle portion 34. A 45 spacing element 35, in the form of a sleeve, is drawn over the screw bolt 29, it serving to hold the said lever in proper relation to the lug 31.

The two shells 11 on the corner-posts, forming 50 an end member of the bedstead, may be connected in any suitable manner, for instance by an angle bar 36, which is fastened by screws 37, or otherwise, to lugs 38, the latter being, preferably, made integral with 55 the two shells.

The operation of the corner-fastening is as follows: If the bedstead is to be provided with an ordinary spring mattress, the angle bars 19 are inserted into the shells in the 60 manner indicated in Figs. 1 to 4, inclusive, of the drawings, in which the flanges 26 of the said bars are disposed horizontally in contact with the top walls 13 of the shells. In order to permit of such insertion, obviously, the lever 28 must be moved in the

direction of the arrow shown in Fig. 2 of the drawings, so as to disengage its side cam face from the lug 31 and to bring the cam face 32 to a distance from the top wall of the shell sufficient to permit of convenient 70 insertion of the angle bar. After the angle bar has been put into place, the lever is shifted into the position shown in Figs. 1 to 4, inclusive, of the drawings, whereby the inclined portion 18 of the plate member 17 75 is forced against the strip 24 of the angle iron, thereby clamping the latter against the outer side wall 15. Simultaneously therewith, the end cam face of the lever clamps the flange 26 of the angle bar against the top 80 wall 13 of the shell. If it is intended to remove the angle bar from the shell, the lever 28 is disengaged from the flange 26 of the angle bar, whereby the yielding portion of the shell is permitted to recede from the 85 angle bar.

If it is desired to use a box spring on the bedstead, the angle bar must be reversed, that is to say it must be brought into the position shown in Fig. 5 of the drawings, in 90 which the flange 26 extends vertically, it being in abutment with the outer side wall 15 of the shell. The lever 28 is then forced into clamping position, it causing the portion 18 of the wall 17 to grip the inwardly 95 bent section 27 of the angle iron bar. The cam face 32 on the said lever does not function in this case. It is to be observed, however, that, inasmuch as the portion 18 of the plate member 17 is inclined, it has a tendency to clamp the angle bar against the top 100 wall 13 and the outer side wall 15 of the shell. The plate member 17, lever 28, bolt 29 and spacing element 35 do not interfere with the insertion of the angle bar, by reason of the latter being provided with the cut off portion 23.

It is obvious that, while herein the shell has been described as made of one integral piece by stamping operations, the same may 110 be otherwise produced, without departing from the invention.

What I claim is:—

1. In a corner-fastening for bedsteads, the combination with a corner-post, of a 115 hollow rectangular shell fastened thereto, an angle bar of the bed-bottom supporting frame extending into said shell, said shell including a rigid portion engaging the outer face of said angle bar and a yielding 120 portion capable of being brought to bear against the inner face of said angle bar, and means mounted upon said shell for causing the yielding portion thereof to clamp said angle bar against the rigid portion of said 125 shell.

2. In a corner-fastening for bedsteads, the combination with a corner-post, of a hollow rectangular shell fastened thereto, an angle bar of the bed-bottom supporting 130

- frame extending into said shell, said shell including a rigid portion engaging the outer face of said angle bar and a yielding portion capable of being brought to bear 5 against the inner face of said angle bar, and a cam lever mounted upon said shell for causing the yielding portion thereof to clamp said angle bar against the rigid portion of said shell.
- 10 3. In a corner-fastening for bedsteads, the combination with a corner-post, of a hollow rectangular shell fastened thereto, an angle bar of the bed-bottom supporting frame extending into said shell, said shell 15 including rigid portions engaging the outer face of said angle bar and a yielding portion capable of being brought to bear against the inner face of said angle bar, and a lever mounted upon said shell having a 20 cam face for causing the yielding portion of said shell to clamp said angle bar against the rigid portion thereof, said lever having a further cam face adapted to bear against the inner face of said angle bar for clamp- 25 ing the same against said shell.
4. In a corner-fastening for bedsteads, the combination with a corner-post, of a hollow rectangular shell fastened thereto, an angle bar of the bed-bottom supporting 30 frame extending into said shell, said shell including a rigid portion engaging the outer face of said angle bar and a yielding portion capable of being brought to bear against the inner face of said angle bar, 35 said yielding portion being provided with a lug, and a cam lever mounted upon said shell and co-operating with said lug for causing the yielding portion of said shell to clamp said angle bar against the rigid 40 portion thereof.
5. In a corner-fastening for bedsteads, the combination with a corner-post, of a hollow rectangular shell fastened thereto, said shell including two parallel side walls, 45 a top, a bottom portion extending from one of said side walls toward the other side wall
- and merging into an upwardly extending plate member between said side walls, said plate member having an inclined portion extending toward the junction line of said top wall and one of said side walls, said plate member being yieldable, an angle bar of the bed-bottom supporting frame extending into said shell with its horizontal flange in abutment with the inner face of said top 50 wall and with its vertical flange in contact with one of said side walls, said vertical flange resting upon said bottom, and means mounted upon said shell for causing the yielding portion thereof to clamp said angle 55 bar against one of said side walls.
6. In a corner-fastening for bedsteads, the combination with a corner-post, of a hollow rectangular shell fastened thereto, said shell including two parallel side walls, 60 a top, a bottom portion extending from one of said side walls toward the other side wall and merging into an upwardly extending plate member between said side walls, said plate member having an inclined portion 65 extending toward the junction line of said top wall and one of said side walls, said plate member being yieldable, an angle bar of the bed-bottom supporting frame extending into said shell with its horizontal flange 70 in abutment with the inner face of said top wall and with its vertical flange in contact with one of said side walls, said vertical flange resting upon said bottom, and a lever pivoted to said shell having a cam face for 75 causing the inclined portion of said yielding shell section to clamp said angle bar against one of said side walls, said lever having a further cam face adapted to bear 80 against the horizontal flange of said angle 85 bar and capable of clamping the same against the top wall of said shell.

Signed at New York, in the county of New York and State of New York, this 26th day of September, A. D. 1921.

MORRIS LOWY.
